COMBINATION DEMONSTRATION AND DISPLAY UNIT

James D. Graham, Manitowoc, Wis., assignor to
Hamilton Manufacturing Company, Two Rivers,
Wis., a corporation of Wisconsin

Filed Oct. 15, 1962, Ser. No. 72,117

Term of patent 14 years

(Cl. D80—11)

FIG. 1 is a rear perspective view taken from one side of a combination demonstration and display unit showing my new design.

FIG. 2 is an elevational view thereof taken from the side opposite that shown in FIG. 1;

FIG. 3 is a top plan view thereof;

FIG. 4 is a front elevational view thereof;

FIG. 5 is a fragmentary front elevational view thereof, the top doors being in an open position, the dots fragmentarily shown, which represent apertures in a perforated board, on the inside center panel of each door being continuous throughout said panel.

The dominant features of my design reside in the portions shown in full lines in the drawings.

I claim:

The ornamental design for a combination demonstration and display unit, substantially as shown and described.
